UNITED STATES PATENT OFFICE.

PHILIP BILLINGHURST, OF GOWAN BRAE, MUSSOORIE, INDIA.

INTERNAL-COMBUSTION TURBINE.

No. 795,889.

Specification of Letters Patent.

Patented Aug. 1, 1905.

Application filed April 29, 1904. Serial No. 205,459.

To all whom it may concern:

Be it known that I, PHILIP BILLINGHURST, of Gowan Brae, Mussoorie, India, have invented certain new and useful Improvements in and Connected with Internal-Combustion Turbines, of which the following is a specification.

This invention relates to a turbine-motor designed for actuation by a mixture of gas or oil vapor and compressed air and comprising a rotating cylinder inclosed in a stationary casing and fitted with a web or partition carried in helical convolutions from end to end of the cylinder, vanes being fitted between the convolutions of such contour as to form a sinuous star-shaped passage or passages for the flow of the gaseous products of combustion through the helix. In conjunction with this turbine or a series of such turbines when used for marine propulsion or for like purposes may be also arranged a gas-maker or vapor-generator for starting purposes, a gas or air pump or compressor discharging into a gas and air tank or reservoir, an equalizer, to which oil and the mixture of compressed gas and air from the reservoir are admitted, and when required a small monitor-turbine arranged to operate the gas or air pump and to govern the speed of the main motor or motors.

The invention is illustrated in the accompanying drawings, in which—

Figure 1 is a longitudinal section through the motor-turbine on line 1 1 of Fig. 2, and Fig. 2 a cross-section thereof. Fig. 3 is a longitudinal section of the oil, gas, or vapor generator used for starting purposes. Fig. 4 represents the air and gas pressure equalizer in longitudinal section. Fig. 5 shows the motor-turbine as applied to the driving-axle of a locomotive or motor-car; and Fig. 6 is a plan representing three motors as arranged for marine propulsion and showing also the gas-maker, air and gas pump, reservoir, equalizer, monitor-motor, and connections.

As shown, the improved motor-turbine comprises a stationary outer casing or cover A and an inner cylindrical rotator B, between which parts is a space C, to which air and gas or oil vapor are admitted at high pressure. The rotator B is carried upon a shaft D by means of "spiders" or perforated disks d, keyed thereto and fixed at their peripheries to a tube B', concentric with the rotator-shell and forming part of the rotator, which is thus of annular cylindrical form. Around the annular space within the shell B is carried a web

or partition-plate B² in helical form, as shown at Fig. 1, and the space between the convolutions of the web B² is fitted with vanes B³ B⁴ of the star-like shape shown at Fig. 2, the vanes B³ being secured around the tube B' and the vanes B⁴ to the shell B, while a sinuous passage B⁶ is left between them.

The outer casing A is filled with oil or water to such a level that the rotator is in contact therewith and is thereby kept cool, and when oil is employed vapor is generated therefrom to mix with the gaseous contents of the casing. Air or a mixture of gas and air under pressure is admitted to the interior of the casing A through any suitable connection, such as the pipe S, and thence a portion of the mixture passes from time to time through an inlet-valve E in the closed end of the rotator, said valve opening against the pressure of a spring e into a chamber F within the rotator B. From the chamber F the explosive mixture passes through a check-valve G, also closed by a spring g, but of lighter power, to prevent back explosions, and thence into the sinuous passage B⁶ between the vanes B³ B⁴ in the space between the convolutions of the web B². Immediately after entering the rotator-helix on clearing the check-valve G the gaseous mixture passes an igniting-coil H and is exploded to actuate the rotator, the products of combustion passing through the sinuous passage B⁶ between the vanes and finding its way into the end space B⁵, which is closed off from the tube B' by an end disk b' and exhausting through a hollow gudgeon H³ and exhaust-pipe H' to the atmosphere, the exhaust being carried round a fan I at the end of the rotator.

The igniting-coil H is composed of a non-conductor, which is kept at a bright heat by coils of wire of high resistance heated by an electric current from a battery or other source, the current being supplied through insulated wires h, carried along the shaft D from slip-rings h' thereon pressing on terminals of said wires.

The rotator-shaft is supported at the inlet end in a bearing formed by a stuffing-box or packing-gland I' on the end of the outer casing A, and at its opposite end the weight of the rotator is carried by an outside journal-bearing J on a standard J', while the hollow gudgeon H³ at the rotator end is formed externally with rings which enter corresponding recesses in a thrust-block K, to which oil

is supplied, so as to maintain a gas-tight joint by means of the oil, the surplus oil overflowing into the casing A.

In the operation of the motor the exploding gas passing through the helical and star-shaped vanes loses its heat and pressure in revolving the rotator B and is thereafter exhausted at atmospheric pressure into the exhaust-pipe. The air and gas or vapor within the outer casing A and around the shaft within the tube B' absorb the heat, as also does the oil in contact with which the rotator revolves, the oil being thereby vaporized.

The inlet-valve E only opens to admit a portion of the gaseous mixture within the outer casing A when the pressure of the mixture is such as to overcome the power of the spring e, and the valve closes to prevent back explosion. On the strength of the valve-spring and on the gaseous pressure depends the speed of the rotator, to which the gaseous mixture is admitted at any part of its rotation. The valve E thus opens and closes under the pressure of the gas within the chamber C irrespective of the speed of the motor and is only controlled by the pressure of the gases. It allows the motor to start at any position immediately the gas-cock admitting the gas to the casing is opened. The check-valve G, the spring of which is lighter than the spring of the valve E, at once permits the passage of the gaseous mixture, and as the valve G closes in advance of the inlet-valve E the prevention of back explosions is insured.

The gases after explosion by the igniting-coil H rush round and round the helical passage between the vanes, striking against their corrugated surfaces till their temperature falls to a degree suitable for exhausting.

The gaseous mixture may be oil-vapor generated from the oil within the casing or forced into the casing A along with air, or it may be composed of power-gas to which air is added, the power-gas and air being compressed by a pump and being enriched, if desired, by oil-vapor generated within the casing by the heat of the rotator in contact with the oil. To facilitate such generation of oil-vapor, a series of scoops b² may be fitted on the rotator B to raise the oil in the bottom of the casing A and drop it during rotation on a serrated enlargement H² of the hollow gudgeon H³.

For starting the engine by supplying gas to it a gas-maker is employed, consisting of a casing L, into which oil from a tank L² is dropped through a pipe l onto a bundle of wires l' to atomize it and cause the spray to drop onto the bottom, which is arched and heated by the flame of a gas-burner L', which may be supplied from the casing, as shown in Fig. 3. An air-pump M, which may be arranged and connected to the casing L by piping M', as indicated at Fig. 6, draws off the gas which is at atmospheric pressure and compresses it along with a suitable supply of

air, the mixture being then delivered to a reservoir and equalizer and thence into the casing A or direct into the casing A, as shown at Fig. 5. The gas-maker may be cut out after the motor is heated up to generate vapor from the oil contained in the casing A.

In large installations, as indicated at Fig. 6, an air or gas pump M is driven by a monitor-motor N, which may be similar in every way to but of much smaller dimensions and power than the motors A A A and which may also be arranged to drive a dynamo O for general lighting purposes. The monitor N is furnished with a governor O', which actuates a lever operating the cock O², supplying the gas, and the speed at which the monitor is driven determines the speed of the larger motors by its action in operating the air-pump which supplies the motors with air or gas and air under pressure. The compressed air is delivered by a pipe p to an air and gas tank or reservoir P, and thence it passes by a pipe q, furnished with valves, to an equalizing-tank Q, (shown detached in Fig. 4,) partially filled with oil by a pipe r from an oil-tank R'. From the equalizer Q the compressed air and oil-vapor pass by piping S, furnished with valves s, into the outer casings of each of the motors A and the monitor-motor N, a supply of oil being carried along with the compressed air. At starting a supply of gas may be taken from the gas-maker L to mix with the compressed air; but when the motors are heated up the gas-maker may be cut off, and the vapor generated from the oil-supply to the motor is then used in conjunction with the compressed-air supply to form the explosive mixture for driving the motors.

Having now described my invention, what I claim, and desire to secure by Letters Patent of the United States, is—

1. An internal-combustion turbine comprising, in combination, a stationary casing, to which compressed air and oil or gas is supplied, and a rotator adapted to revolve in said casing, said rotator consisting of cylindrical shells a helical web fitted in said shells and star-shaped vanes attached to said shells within the helical space formed by said web, substantially as described.

2. In an internal-combustion turbine of the kind set forth a stationary casing, a shaft, a rotator fast on said shaft, said rotator comprising annular cylindrical shells, a helical web fitted in said shells and vanes attached to said shells leaving a sinuous helical passage between them: a gas-inlet at one end of said casing a spring-closed valve, an ignition-coil within the casing to explode the admitted gases and an exhaust-opening at the other end of the casing substantially as described.

3. The combination of an internal-combustion-turbine motor composed of an outer stationary casing and an inner rotator within said

casing and rotating in contact with oil therein of an air-compressing pump, a gas and air reservoir, and a pressure-equalizer connected to said reservoir and arranged to deliver compressed air and gas into the motor-casing, substantially as described.

4. An internal-combustion engine, comprising in combination, a hollow casing, a shaft longitudinally disposed in said casing, a rotator on said shaft comprising two annular shells one within the other, a helical web connecting said shells, star-shaped vanes, connected to said shells within the space inclosed by said helical web, a chamber at one end of said rotator an inlet-valve admitting combustible

mixture into said chamber, a spring tending to close said valve a check-valve admitting said mixture into said rotator, a second spring weaker than said first spring tending to close said check-valve, a hollow gudgeon at the other end of said casing and an exhaust-pipe connected to said gudgeon, substantially as described.

In testimony whereof I have signed my name to this specification in the presence of two subscribing witnesses.

PHILIP BILLINGHURST.
